UNITED STATES PATENT OFFICE.

LEANDER S. LONG, OF NEW CASTLE, PENNSYLVANIA.

SMOKE-BELL SUPPORT.

No. 920,164.

Specification of Letters Patent. Patented May 4, 1909.

Application filed August 8, 1908. Serial No. 447,614.

To all whom it may concern:

Be it known that I, LEANDER S. LONG, a citizen of the United States, residing at New Castle, in the county of Lawrence and State 5 of Pennsylvania, have invented a new and useful Smoke-Bell Support, of which the following is a specification.

This invention relates generally to smoke-bell supports, and specifically to devices of 10 the above mentioned class which are adapted to be supported by a gas fixture.

The objects of the invention are, the provision in a merchantable form, of a smoke-bell support which shall be inexpensive to 15 manufacture, facile in operation and devoid of complicated parts; the provision of a smoke-bell support which may be readily attached to standard gas connections, firmly retained thereon, and readily removed there- 20 from; the provision of a device in which the smoke-bell is removable for cleaning, and adjustable with respect to the axis of the burner to which it is attached.

With these objects in view, together with others which a perusal of this specification will reveal to those skilled in the art, the invention consists in the novel construction and arrangement of parts hereinafter described, delineated in the accompanying 30 drawings and particularly pointed out in the appended claims, it being understood that divers changes in the form, proportions, size and minor details of the structure may be made without departing from the spirit or 35 sacrificing any of the advantages of the invention.

Similar numerals of reference are employed to indicate corresponding parts throughout the several figures of the drawings.

40 In the accompanying drawings, Figure 1 is a side elevation, showing my invention attached to a conventional gas burner; Fig. 2 is a top plan view showing the connections between the smoke-bell 15, clip 16, and bracket 9; Fig. 3 is a vertical longitudinal section through the diameter of the thimble 5.

To the accompanying drawing reference may now be had, in which is shown a common gas cock 1, having an upright, ex- 50 teriorly threaded section 2, the numeral 3 designating an interiorly threaded sleeve adapted, when my invention is not used, to be screwed up on the section 2, a burner-tip

being introduced into the mouth 4 of the sleeve.

In carrying out my invention, I provide a tubular thimble 5, threaded interiorly at its lower end, as shown at 6. The upper portion of the thimble 5 is of less diameter than the lower portion, the difference between the 60 diameters creating the shoulder 7. The upper portion of the thimble 5 is threaded as shown at 8. I further provide a bracket 9, having a flattened loop 10 adapted to engage the upper portion of the thimble 5 and 65 to rest rotatably upon the shoulder 7. The bracket 9 may be of any form; preferably however, as shown, it consists of a straight horizontal portion 11, a straight upright portion 12, an outwardly extending U-shaped 70 portion 13 and an upper terminal 14, all formed integrally, the portions 11, 12 and 13 being in a common plane, and the portions 10 and 14 occupying parallel planes, sub- 75 substantially at right angles to the axis of the portion 12. In forming the upper terminal 14, I bend the end of the bracket 9 sharply 80 upon itself and flatten the portions thus brought into contact. I further provide a smoke-bell 15, which may be of any form, and to the smoke-bell 15, I attach, by any of the well known methods of the tin-smith's craft, the clip 16; I have shown the rivets 17 as adapted to the end sought to be effected.

In its preferred form, the clip 16 has its 85 sides 18 inwardly flexed toward each other and adapted to engage, with slight friction, the flat terminal 14 of the bracket 9. The end 19 of the clip is bent upon itself and brought 90 down into close contact with the tops of the rivets 17 into the travel of the terminal 14 of the bracket, as shown in Figs. 1 and 2.

In the case of a common gas fixture, assembled in the ordinary manner, the threaded sleeve 3 is unscrewed from the upright 95 section 2 and upon the section 2 is mounted the thimble 5, the threads 6 engaging the threaded portion of the member 2. The flattened loop 10 is then slipped over the top 100 of the thimble 5 and the threaded sleeve 3 screwed down upon the thimble 5, engaging the threads 8 and forcing the loop 10 downward upon the shoulder 7. When the bracket 9 is thus mounted upon the thimble 5, its removal will be of rare occurrence. 105 The smoke-bell, 15, however, must be fre-

quently removed for cleaning, and the slide-
able connection between the clip 16 and the
terminal 14 furnishes a means whereby the
smoke-bell 15 may be easily removed and
replaced.

A smoke-bell is ordinarily disposed con-
centrically with the burner, and in this posi-
tion it is ordinarily most effective. In cer-
tain cases however, air-currents deflect the
rising smoke, and an adjustment of the posi-
tion of the smoke-bell becomes necessary.
In my invention, it is obvious that the clip
16 may be slid upon the terminal 14, and the
loop 10 rotated upon the thimble 5, thus
adjusting the position of the bell 15 for vary-
ing lines of smoke-drift.

Having thus described my invention, my
claims are as follows:

1. In a device of the class described, a
smoke bell and a supporting bracket; a clip
comprising sides inwardly bent and arranged
to receive slidably the terminal of the

bracket, and an end bent upon itself and
brought into the travel of the terminal of
the bracket; means for attaching the clip
to the smoke bell.

2. In a device of the class described, a
bracket comprising a lower terminal ar-
ranged for rotatable mounting upon a gas-
burner; an upright portion rising from the
lower terminal; a U-shaped portion extend-
ing outward beyond the upright portion and
having its lower arm integral with the up-
right portion; an inwardly extending upper
terminal integral with the upper arm of the
U-shaped member; a smoke bell slidably
mounted upon the upper terminal.

In testimony that I claim the foregoing as
my own, I have hereto affixed my signature
in the presence of two witnesses.

LEANDER S. LONG.
